(57) **CLAIM**

I claim the ornamental design for a lid, as shown and described.

DESCRIPTION

FIG. 1 is a top perspective view of one embodiment of the claimed design;
FIG. 2 is a bottom perspective view of the claimed design of FIG. 1;
FIG. 3 is a side view of the claimed design of FIG. 1;
FIG. 4 is a top view of the claimed design of FIG. 1;
FIG. 5 is a bottom view of the claimed design of FIG. 1;
FIG. 6 is a cross-section view of the claimed design of FIG. 1 taken along line 6-6 in FIG. 4;
FIG. 7 is a top perspective view of another embodiment of the claimed design;
FIG. 8 is a bottom perspective view of the claimed design of FIG. 7;
FIG. 9 is a side view of the claimed design of FIG. 7;
FIG. 10 is a top view of the claimed design of FIG. 7;
FIG. 11 is a bottom view of the claimed design of FIG. 7; and,
FIG. 12 is a cross-section view of the claimed design of FIG. 7 taken along line 12-12 in FIG. 7.

In the drawings, the evenly-spaced broken lines show portions of a lid that form no part of the claim; the dash-dot-dash lines represent boundaries of the claimed design and form no part thereof.

1 Claim, 12 Drawing Sheets
